Attorney

UNITED STATES PATENT OFFICE.

CHARLES H. MELVIN, OF MOLINE, ILLINOIS, ASSIGNOR TO DEERE & COMPANY, A CORPORATION OF ILLINOIS.

PLOW.

1,184,473.

Specification of Letters Patent. Patented May 23, 1916

Application filed October 21, 1909, Serial No. 523,882. Renewed April 14, 1913. Serial No. 761,050.

To all whom it may concern:

Be it known that I, CHARLES H. MELVIN, a citizen of the United States, residing at Moline, in the county of Rock Island and State of Illinois, have invented certain new and useful Improvements in Plows, of which the following is a specification, reference being had therein to the accompanying drawing.

10 This invention relates to improvements in plow bodies and especially in bodies adapted for use in steam plows in which a number of individual plows are secured to the same frame.

15 The object of the invention is to provide a plow body in which the point or share may be readily and quickly detached from or attached to the other parts of the plow body.

20 In the accompanying drawings I have shown one embodiment of my invention. It will be understood, however, that various changes may be made in the arrangement of parts and in structural details within 25 in the scope of my invention.

Of the drawings—Figure 1 is a perspective view taken from a point near the front. Fig. 2 is a body perspective view taken from beneath and showing the attaching means. Fig. 3 is a detail view of the plow share. Fig. 4 is a bottom plan view. Fig. 5 is a cross sectional detail view of the share locking lug.

Referring to the drawings, 1 represents the plow point or share, 2 the mold-board, 3 the land-side; and 4 the frog to which the other parts are attached.

5 is a standard to which the main frame part of the frog is attached and by means of which the plow body as a whole is moved.

As to the details of the frog, there may be considerable variation, but in the preferred form, as shown in the drawings, it comprises three separate pieces of metal 45 which are bolted together. These three pieces are, first, the frame 4 to which are connected the mold-board and the land-side by means of suitable bolts or rivets; second, the bracket 11 which is connected 50 to the frame 4 by means of the bolt 16; and third, the clip or finger 14 which is connected with the bracket 11 (and preferably also with the mold-board) by means of the bolt 15. As stated above, the frog of my plow 55 is that part of the plow which serves to

support and connect together the other parts, and the elements 4, 11 and 14 are all essential for this function. The main frame part 4 of the frog is bent and forged into suitable shape to conform to the inner surfaces of the land-side, the mold-board and the share. The parts 11 and 14 are shaped and positioned to co-operate with the mold-board and with the share in a manner to be 60 fully described.

I herein refer to the "toe" of the frog, meaning thereby the forward portion which guides the share into its proper position in relation to the moldboard and holds it under the stress from the bolt 10 against lateral displacement, this toe being the part which comprises the camming edge at 14 and the forward part of the landside flange 7. This element of the frog, when the bolt 10 is drawn tightly to place, first, imparts lateral draft on the share to bring its landside flange 7 tightly against the land-side flange of the frog, second, draws the bottom face of the share tightly against the upper face of the front part or portion of 75 the frog, and, third, maintains tightness, laterally, of fit, because of the inclination of the camming edge at 14 to the longitudinal line of the landside.

The plow share 1 is formed with a section 6 adapted to aline with the mold-board, and with a section 7 at an angle to the section 6 and adapted to aline with the landside 3. The sections 6 and 7 each engage with and are supported by the forward end 85 of the frame 4 of the frog. The forward side of the share is ground to a sharp edge, and it is chiefly for the purpose of sharpening this edge from time to time that the share is made detachable.

95 On the inner side of the section 7 is located the stud or lug 8. This lug, in its preferred form, consists of a staple formed of a round iron rod, the ends of which are passed through countersunk holes in the part 7 and riveted over as shown in Fig. 5. If desired, however, the projection may be formed integrally with the share, or in any other preferred way. The frame 4 of the frog is provided with a slot 9 into which 105 the lug 8 projects. The engagement of the lug and slot prevents any sliding or twisting of the share relative to the plow body. The land-side section 7 of the share is provided with a rearward extension 7^a which 110

is adapted to underlie and engage the lower forward corner of the moldboard 2 to assist in holding the share in proper position. To the blade 6 of the share I pivotally attach the threaded bolt 10. The bracket 11 of the frog is provided with an eye through which the bolt 10 may pass. The bracket is so located relative to the point of pivotal attachment of the bolt 10 that when the plow parts are in place the bolt 10 will lie at an acute angle to the line of contact of the share and the mold-board. When the bolt 10 is tensioned, by means of a nut 12, not only is the share drawn firmly against the mold-board, but it is also drawn diagonally backward so that the section 7 with the lug 8 is forced against the frame 4 of the frog.

13 is an abutment attached to the share 20 and engaging the underside of the mold-board, when the share is in place. The outer side of the frog at 14 is extended forward to engage the under side of the share when the share is in place. The abutment 13 therefore cooperates with the frog in holding the mold-board and the mold-board section of the share in proper register with each other. As shown in the drawings, the abutment 13 and the outer part of the frog 30 are formed with beveled edges in order to aid in the attachment of the share to the plow body. After the share has been removed and it is desired to replace it, it is placed in approximate position, with the toe 35 of the frog (extending from the clip 14 on the one hand to the land-side part of the frame on the other hand) lying between the land-side flange 7 and the abutment 13. It is clear that when the parts are in this position, the toe part of the frog will overlie the stud 8 and that the upper wall of the slot 9 will serve as an inclined shoulder for engaging the stud. When in the position just described, a slight pressure at the rear 40 part of the share causes the abutment 13 to slide upon the outer part of the toe of the frog, thus drawing the stud 8 into the slot 9. It is then only necessary to screw the nut 12 onto the bolt 10 and thus securely 50 lock the share in position.

When the share is in place the toe of the frog acts in a number of ways to hold it against displacement. The land-side part of the toe of the frog, by engaging the land-side flange of the share, prevents movement in one direction, and the clip 14 at the opposite side of the toe of the frog by engaging the abutment 13, prevents movement in the opposite direction. At the same time the inclined shoulder at the upper edge 55 of the slot 9 by its engagement of the stud 8 beneath it, serves to prevent any upward movement of the share with respect to the frog.

56 The use of the elongated stud or lug 8

is especially advantageous, as it aids in preventing any angular movement of the share relative to the frog. It is desirable to secure as firm an engagement as possible between this part of the share and the frog, 70 as the section 7 is untempered and, therefore, much stronger and less brittle than the tempered blade 6.

While I have shown and described a land-side 3, it will be understood that this is not 75 an essential part of my invention and that it may, under certain circumstances, be omitted.

What I claim is:

1. In a plow, the combination of a frog 80 having two parts at an angle to each other, a mold-board secured to one of the parts, a share having a land-side section and a mold-board section adapted to engage respectively with the said two parts of the 85 frog, a tension device for drawing the share into firm engagement with the frog, and a one-piece U-shaped staple having its ends extending through and riveted in apertures in the land-side section of the share, the said 90 staple being arranged to extend through a corresponding aperture in the said land-side part of the frog and hold the share against movement relative to the other plow parts. 95

2. In a plow, the combination of a frog, 100 having two parts at an angle to each other, a mold-board secured to one of the parts, a share having a land-side section and a mold-board section adapted to engage respectively with the said two parts of the 105 frog, a tension device for drawing the share into firm engagement with the frog, and a device provided with parts extending through and secured in apertures in the 110 land-side section of the share, the said device being longitudinally extended in a direction parallel to the said share section and arranged to enter and engage with the side of a corresponding aperture in the said land-side part of the frog to hold the share against movement relative to the other plow parts.

3. The combination in a plow, of a mold-board, a frog, a detachable share having 115 a mold-board section and a land-side section, the said land-side section having a longitudinally elongated projection and the said frog having a similarly elongated aperture into which the projection may enter 120 to prevent relative movement of the plow share and body, the walls of the aperture engaging the projection on all sides, and a tension device between the plow share and the plow body having its line of tension at an acute angle to the line of contact between the share and the body whereby the said tension device tends to draw the said projection into the said aperture. 125

4. In a plow, the combination of a frog 130

- having a moldboard part and landside part at an angle to each other, a moldboard secured to the moldboard part of the frog, a detachable share having a moldboard section and a landside section at an angle to each other and adapted to engage respectively with the moldboard part and the landside part of the frog, the said landside section of the share being extended rearward 5 and shaped to engage with the under side of the moldboard, a bolt connected at its forward end to the under part of the moldboard section of the share at a point remote from the landside section, and means engaging with the frog for tensioning the bolt. 7'
5. In a plow, the combination of a frog having a moldboard part and landside part at an angle to each other, the said landside 10 part having a longitudinal slot closed at both ends, a moldboard secured to the moldboard part of the frog, a detachable share having a moldboard section and a landside section at an angle to each other and adapted 15 to engage respectively with the moldboard part and the landside part of the frog, the said landside section of the share being extended rearward and shaped to engage with the under side of the moldboard, a projection 20 on the landside section of the share positioned to enter the slot in the landside part of the frog, a bolt connected at its forward end to the under part of the moldboard section of the share at a point remote from the landside 25 section, and means engaging with the frog for tensioning the bolt whereby the share is drawn laterally and longitudinally, the said projection entering the slot and the extension on the landside section engaging the 30 under side of the moldboard. 35
6. The herein described plow share, having the moldboard section 6, a landside section 7 with the backward extension 7' fitting under the moldboard, and the lug 8 on its landside section, and adapted to have the bolt 10 permanently secured to its moldboard section whereby the share is adapted to be drawn longitudinally, laterally and vertically to its seat when combined with (A) a moldboard 2, and with (B) a frog having (a) a part arranged to engage the said section 6, (b) an apertured part arranged to engage the said section 7 and to receive the lug 8, and (c) an apertured part adapted to receive detachably the said bolt 10. 40
7. The herein-described plow share, having the mold-board section 6, the land-side section 7, the lug 8 on the land-side section, the bolt 10 secured to the mold-board section (whereby the share is adapted to be drawn longitudinally and laterally to its seat when combined with a mold-board 2 and with a frog having a part arranged to engage the said section 6, an apertured part arranged 45 to engage the said section 7 and receive the lug 8, and an apertured part adapted to receive the said bolt 10) and means adapted to co-operate with the frog to hold the share and the mold-board in register with each other in the same plane. 7'
8. The combination with a plow body, of a share having a landside flange, an abutment on the lower face of said share, an inwardly projecting stud on said landside flange, a frog having a projecting toe portion fitting between said flange and said stud and said abutment and extending over said stud and a longitudinally extending bolt for securing said share to the plow body, substantially as described. 75
9. In a plow body, a share having a landside flange and an abutment on its lower face, a frog having a toe fitting between said flange and said abutment, a stud on said landside flange extending beneath said toe, and a longitudinally extending bolt for securing said share in position, substantially as described. 80
10. In a plow body, a share having a landside flange and an abutment on its lower face, a frog having a toe fitting between said flange and said abutment and having an inclined shoulder arranged to engage said abutment, said landside flange having a part extending beneath said toe, and a longitudinally extending bolt connected to said share at its forward end and to a part of the plow body at its rear end, substantially as described. 90
11. The combination with a plow body, of a share having a landside flange, a projecting abutment on its inner face and an inwardly projecting stud on its landside flange, a frog provided with a toe portion fitting between said flange and said share and provided with shoulders detachably engaging said abutment and said stud, a longitudinally extending bolt connected at its forward end to said share and a part secured to the plow body to which the rear end of said bolt is detachably connected, substantially as described. 100
12. The combination with a plow body, a share having a landside flange, an abutment on its lower face, and an inwardly projecting stud on said landside flange, a frog having a projecting toe portion fitting between said flange and said abutment and extending over said stud, said toe portion having an inclined shoulder arranged to engage said abutment, and a longitudinally extending bolt connected to said share at its forward end and to a part of the plow body at its rear end, substantially as described. 115
13. The combination with a plow body, of a share having a landside flange and an abutment on its lower face, a frog having a projecting toe portion fitting between said abutment and said flange, said share having a part extending beneath said toe portion, 120

4
and a longitudinally extending bolt for securing said share to the plow body, substantially as described.

14. The combination with a plow body, of
5 a share having a landside flange and an
abutment on its lower face, a frog having a
projecting toe portion fitting between said
abutment and said landside flange and hav-
ing an inclined cam shoulder engaging said
10 abutment, said share having a lug extend-

ing beneath said toe portion and a longitudinally extending bolt for securing said share to the plow body, substantially as described.

In testimony whereof I affix my signature, 15
in presence of two witnesses.

CHARLES H. MELVIN.

4
and a longitudinally extending bolt for securing said share to the plow body, substantially as described.

14. The combination with a plow body, of
5 a share having a landside flange and an
abutment on its lower face, a frog having a
projecting toe portion fitting between said
abutment and said landside flange and hav-
ing an inclined cam shoulder engaging said
10 abutment, said share having a lug extend-

ing beneath said toe portion and a longitudi-
nally extending bolt for securing said
share to the plow body, substantially as de-
scribed.

In testimony whereof I affix my signature, 15
in presence of two witnesses.

Corrections in Letters Patent No. 1,184,473.

It is hereby certified that in Letters Patent No. 1,184,473, granted May 23, 1916,
upon the application of Charles H. Melvin, of Moline, Illinois, for an improvement
in "Plows," errors appear in the printed specification requiring correction as
follows: Page 1, line 28, strike out the word "body"; page 3, line 58, claim 7, after
the word "section," second occurrence, insert the words *and adapted to have*; and
that the said Letters Patent should be read with these corrections therein that
the same may conform to the record of the case in the Patent Office.

Signed and sealed this 18th day of July, A. D., 1916.

[SEAL.]
